ELECTRICAL CONNECTION MEANS

Russell A. Funk, Sebewaing, Mich., assignor to
 H. A. Douglas Mfg. Co., Bronson, Mich., a corporation of Michigan

Application March 13, 1941, Serial No. 383,127

5 Claims. (Cl. 173—328)

This invention relates generally to electrical connection means, known in the trade as line connectors, which are adapted to receive conductor terminals.

One particular object is to provide a connector in which the parts thereof may be easily and quickly assembled without the aid of special tools.

Another object is to provide improved means whereby to directly detachably connect together plug conductor terminals, and which when connected function to detachably hold a sleeve of insulating material about same.

Other objects and advantages of the invention will appear hereinafter.

In the drawing accompanying this specification and forming a part of this application, there is shown for the purposes of illustration, one of the many forms which the invention may assume; and in the drawing:

Figure 1 is a longitudinal sectional view of the connector embodying the invention;

Figure 2 is an end view of the insulating member with the terminals removed therefrom;

Figure 3 is a side view of one of the terminals embodying the invention;

Figure 4 is a section taken substantially on line 4—4 of Figure 3; and

Figure 5 is a vertical section through a part of a terminal post depicting another application or use of the type of terminal illustrated in Figure 3.

Referring to the drawing, numeral 1 represents a generally tubular insulating member or sleeve. A pair of plug conductor terminals 2 and 3 are disposed within this sleeve and are directly detachably connected whereby to provide a through electrical connection between conductor wires 4 and 5 to which the terminals are secured.

The sleeve 1 is preferably made oval or oblong in cross-section, and a pair of recesses generally designated 6 and 7 extend inwardly from each end of the sleeve. Each of the recesses 6 and 7 is preferably oblong in cross-section, the purpose of which will be described later, and the axes of said recesses are preferably arranged in spaced apart parallel relation. The recess 6 includes a rather large entrance opening 8 and a smaller aperture 9 which are communicatively connected together, and joined together by a conical or tapered portion 10. The aperture 9 is of a greater longitudinal extent than the opening 8, and its inner extremity is preferably designed to provide a curved or radial abutment 11 which more or less provides a stop whereby to predetermine the extent of the inward movement of the terminal 2 into the recess.

The recess generally designated 7 substantially corresponds in shape and size to the recess 6, and includes an entrance opening 12 and an ap-

erture 13 which are communicatively connected together, and joined by a conical portion 14. The aperture 13 is of a greater longitudinal extent than the opening 12, and its inner extremity 15 is provided with a curved or radial abutment 16 whereby to more or less limit the extent of the inward movement of the terminal 3. It is to be particularly noted that the apertures 9 and 13 intersect each other to provide a generally oblong chamber within which the inner extremities of the terminals 2 and 3 are disposed when the parts are assembled together as illustrated in Figure 1. The abutment 11 forming a part of the aperture 9 is located beyond the center of the sleeve, and the abutment 15 of aperture 13 is also located beyond the center of the sleeve; in other words, said abutments are arranged in offset relation with respect to each other, one on each side of said center.

Each terminal is preferably made from flat sheet metal stock which is formed or fashioned as illustrated in Figures 1 and 3. The terminal 2 includes a large generally tubular cylindrical skirt portion 16 which receives the insulation of the conductor 4; a smaller tubular cylindrical portion 17 which receives the bare end 18 of the conductor; and a resilient extremity generally designated 19. The portions 16 and 17 are preferably joined together by a tapered shoulder portion 20; and that portion of the terminal intermediate the portions 17 and 19 is preferably curved or made concave so as to provide a detent cove or groove 21. The conductor 4 may be attached to the terminal 2 in any suitable manner, but, as herein illustrated, is preferably secured thereto by means of solder; and in order to facilitate such a connection, the opposite and adjacent longitudinally extending meeting edges of the material from which the terminal is made, are preferably notched as indicated at 22 to provide a recess through which fluid solder may be dropped onto the bare end of the conductor wire. In any event, it is desirable to connect the conductor wire to the terminal in such a way that the connection will not, in any way, interfere with the action of the resilient extremity 19.

The resilient extremity 19 of the terminal 2 is preferably provided with a plurality of resilient curved fingers 23, preferably four in number, which are formed by providing longitudinally extending slots 24 in the extremity 19. The extremity 19 is preferably generally spherical or round, and resilient fingers 23 are so constructed and arranged that same may flex independently with respect to each other. Due to the round character of the extremity 19 of the terminal, the fingers 23 are made relatively resilient, yet comparatively rigid, and very durable. In this connection, it is to be noted that the slots 24 which extend longitudinally inwardly from

the extreme end of the extremity 19 terminate short of the base of the detent groove 21.

The terminal 3 corresponds in every particular to the terminal 2, and accordingly it is believed sufficient to state that this terminal includes a resilient extremity 25 and a detent groove 26.

In view of what has been stated above, it should be apparent that to assemble the terminals 2 and 3 with respect to each other and to the insulating sleeve 1, it is merely necessary to insert the generally round extremities 19 and 25 of the terminals into the recesses 6 and 7, until the extremities 19 and 25 engage each other, whereupon further inward movement of the terminals into the chamber formed by the apertures 9 and 13 will at least cause certain of the resilient fingers 23 on each of the terminals to be depressed or compressed toward each other, and at or about the time the extremities 19 and 25 engage the abutments 11 and 15, respectively, the extremities will expand or snap outwardly causing at least one, or more of the fingers on the extremity 19 to snugly fit into the detent groove 26 provided in the terminal 3 and at least one of the fingers on the extremity 25 to cooperate or register with the groove 21 of terminal 2, as clearly illustrated in Figure 1. Thus, the resilient fingers on the extremities 19 and 25 will provide a good mechanical and electrical connection between the terminals 2 and 3, and in view of the fact that the curvature of the detent grooves and extremities 19 and 25 are constructed as shown, a practically continuous line of contact is established, such line being more or less in the form of an ogee curve. Obviously, the extremities 19 and 25 slidably engage the walls defining the apertures 9 and 13 when the terminals are inserted into the recesses. Although the abutments 11 and 15 provide stops that more or less limit the inward movement of the terminals into the sleeve, it will be appreciated that the shoulders or tapered portions such as 10 and 14 may likewise provide stops which may be engaged by the tapered portions 20 of the terminals to limit inward movement of the latter during assembly. The shoulders on the terminals also provide stops for the insulation on conductors 4 and 5 whereby to predetermine the positions of the bared ends of the conductors with respect to the tubular portions 17.

The openings 8 and 12 and the apertures 9 and 13 as set forth above are preferably made oblong in cross-section, and although not essential, is nevertheless desirable in that same allows for radial adjustment of the terminals with respect to each other as same are being assembled or disassembled with respect to the insulating sleeve. In other words, in certain instances the terminals may not be properly formed, or a fin or fins may be left in the sleeve during the molding operation, in which event it might be difficult to press the resilient extremities 19 and 25 past each other into intimate interlocking relation. Obviously, to disassemble the terminals with respect to each other and the sleeve 1, it is only necessary to grasp and pull outwardly on the conductors 4 and 5.

Referring to Figure 4, numeral 27 designates a terminal post provided with a terminal receiving aperture 28. A spring 29 carried by the post normally presses a detent 30 into intersecting relation with respect to the aperture 28 and is

adapted to register with the detent groove 21 of the terminal 2. In view of this construction it should be clearly apparent that the terminals embodied and adapted to be used in conjunction with the line connector as illustrated in Figure 1, may also be used in conjunction with a snap terminal receptacle of the character shown in Figure 5.

In view of the foregoing it will be apparent that improved means have been provided whereby plug conductor terminals may be directly detachably connected to each other and that when connected function to hold an insulating sleeve about same.

Having thus described my invention, it is obvious that various modifications may be made in the same without departing from the spirit of the invention; and, therefore, I do not wish to be understood as limiting myself to the exact form, construction, arrangement, and combination of parts herein shown and described.

I claim:

1. An electrical connector, including a dielectric sleeve, a generally round recess extending inwardly from each end of the sleeve, said recesses being arranged in generally parallel relation with their inner extremities intersecting and overlapping each other whereby to provide a chamber, a pair of terminals disposed in said recesses having resilient portions disposed in said chamber, and said resilient portions being arranged in interlocking relation with respect to each other and to the walls of said chamber whereby said sleeve is held assembled with said terminals.

2. An electric connector including, an insulator, a chamber provided in said insulator, recesses of a size less than that of the chamber extending inwardly from at least two sides of the insulator and communicating with said chamber, terminals disposed in said recesses, and the inner extremities of said terminals having resilient means arranged in said chamber whereby said terminals are pressed into interlocking engagement with each other and against certain walls of the chamber for holding said terminals in assembled relation.

3. Electrical connection means including, a plurality of plug conductor terminals, said terminals having generally split ball portions, and means surrounding said terminals acting on said split ball portions causing them to yield and define a contact line substantially corresponding to an ogee curve.

4. An electrical connector including, an insulator, substantially annular recesses extending inwardly from opposite surfaces of the insulator, the longitudinal axis of said recesses being arranged in parallel relation and spaced apart a predetermined distance so that the inner extremities of the recesses intersect and overlap each other, and terminals secured in interlocking relation with each other in said recesses.

5. An electrical connector including, an insulator, apertures extending inwardly from opposite surfaces of the insulator and intersecting each other adjacent their inner extremities, terminals within the apertures interlocking with each other, and the end walls of said apertures providing abutments adapted to be engaged by the terminals for predetermining the contacting position of said terminals.

RUSSELL A. FUNK.
